CLAIM

The ornamental design for a faucet handle, as shown and described.

DESCRIPTION

FIG. 1 is a perspective view of a faucet handle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is another perspective view thereof, with the spout and another faucet handle engaged.

The dotted line showing of the spout and the faucet handle is for illustrative purposes only and forms no part of the claimed design.
